UNITED STATES PATENT OFFICE.

WILLIAM R. PULKINGHORN, OF LOS ANGELES, CALIFORNIA, ASSIGNOR TO SPRA-O-SAL PRODUCTS, INC., OF LOS ANGELES, CALIFORNIA, A CORPORATION OF CALIFORNIA.

SANITARY DEVICE.

Application filed July 25, 1927. Serial No. 208,227.

This invention relates more particularly to a device designed to be connected in the flushing lines of toilet fixtures for chemicallyizing the water flowing therethrough.

5 It is an important object of my invention to provide a simple device that may be readily mounted in the fluid flushing lines of toilet fixtures to chemicalize the flushing water, whereby to effectually destroy or neutralize noxious odors arising from their use.

A further object is to provide a toilet sanitation device that will hold a relatively large quantity of a disinfecting chemical and arranged to deliver the proper amount of disinfecting solution at each flushing operation.

A still further object is to provide a device that will not only chemicalize the flushing water as used but impart a pleasant odor to the same.

The above and other objects are accomplished by means of the device described herein and illustrated in the accompanying drawings, in which;

25 Fig. 1 is an elevation of the device connected in the flushing lines of toilets.

Fig. 2 is an enlarged central vertical section through the device.

It has heretofore been the usual practice 30 in deodorizing and disinfecting toilet fixtures, to feed the disinfectants from containers to the toilet hoppers, urinals and the like in small minute quantities, a container for each fixture. This method of deodorizing and disinfecting has proved ineffective at 35 times due to faulty apparatus, and also expensive as a larger amount of chemicals are required for the purpose than is necessary to effect the desired result.

40 In the device herein described a large number of toilet fixtures may be supplied from a single device in an extremely efficient and economical manner as the flushing water is chemicalized only during a flushing operation, thus economizing in the use of 45 disinfectants. Further, as a deodorant is employed in connection with the device there will be no necessity of employing a separate deodorant as is now generally the case.

50 Referring now more particularly to the drawings which illustrate one embodiment of the invention, 5 designates the device as

a whole consisting of a cylindrical chemical holder 6 closed at its lower end and provided with a closure member 7 for its open upper end. This closure member has an inlet opening 8 and a discharge outlet opening 9, both openings being connected to the toilet flush line pipes 10 and 11.

The chemical holder 6 is provided on its lower end with a nut 12 formed integrally therewith, and its upper end is exteriorally threaded for engaging the circular flange 13 of the closure member when the device is in assembled condition. Preferably the holder 15 is formed large enough to receive a pound size chemical cartridge 14; as such quantity of disinfecting chemical will serve a large number of fixtures for approximately sixty (60) days without the necessity of renewal.

The top wall 15 of the closure member is provided with a fluid passage way 16 whose ends terminate in the inlet and outlet openings, and just below the top wall 15 are formed two minute oppositely disposed 75 openings 17, 18 in alignment with the inlet and outlet openings that communicate with the interior of the chemical holder. By means of these openings the water flowing through fluid passageway will induce a flow 80 through the upper portion of the chemical container into the fluid passing through the flush line pipes. As the openings 17 and 18 are very small it will be apparent that the induced flow through the chemical container 85 will carry only a sufficient quantity of the chemicalized solution to impregnate the volume of water used in a flushing operation.

In tests which I have made I have found that "permanganate of potassium" is one of 90 the best disinfectants, and as it is inexpensive the cost of operation of the device will be comparatively low. It will be understood that other disinfectants that are soluble in water may be employed with equally satisfactory results.

As some of the disinfectants employed may give off an unpleasant odor I have provided a means in connection with the device for imparting a pleasing odor to the chemicalized flushing water, the means as shown preferably consisting of a cylindrical liquid well 20 open at its upper end and interiorly screw-threaded for attachment to

an exteriorly threaded annular flange 21 formed on the underface of the closure top wall 15, the flange being centrally disposed with respect to the container 5 therebelow. The wall 15 of the closure is provided with a central opening 22 in which is mounted a wicking 23, the lower end being disposed in the liquid of the well 20 while its upper end projects into the fluid passage- 10 way of the closure member. From the above it will be apparent that the wick 23 will carry a small amount of liquid deodorant by capillary attraction into the water flow in an amount sufficient to correct any un- 15 pleasant odor that might arise from the use of a disinfectant.

The sanitary device may be connected in the flushing lines that supply a large number of toilets, such as are found in hotels, 20 apartment houses, or office buildings, and it may be also successfully and economically employed in connection with single toilets with equally satisfactory results.

In order that the chemical cartridge 14 25 may be replaced by a fresh one when it becomes exhausted, globe valves 25 and 26 are mounted in the main flush line, a valve adjacent each inlet and outlet openings to control the flow of water therethrough, and in 30 order to prevent the disinfectant solution from co-mingling with the fluid in the flush line before it enters the device especially when the toilets are out of operation, a check valve 27 is disposed in the flush line between 35 the fluid inlet and globe valve 25.

From the above it will be clear that I have provided an extremely simple device that may be advantageously and economically

employed to disinfect toilet fixtures and correct unpleasant odors arising therefrom.

What I claim is:

1. A sanitary device for toilet fixtures comprising a container for chemicals having a fluid passage above its upper end adapted for connection in a fluid supply 45 pipe line, and a wick leading from the container into the fluid passage for delivering the chemical from the container to the fluid passage, whereby the water flowing through the passage will be chemicalized.

2. A sanitary device for toilet fixtures comprising a container for chemicals, a closure for the upper end of said container having a fluid passage adapted for connection in a fluid supply line, said closure having inlet and outlet openings communicating with the fluid passage, and a container for holding a deodorant connected to said closure, said container having an opening 55 communicating with the fluid passage.

3. A sanitary device for toilet fixtures comprising a chemical holder, a closure cap for said holder having a transversely disposed fluid passageway of uniform diameter formed thereabove, said passageway adapted to be connected to a fluid pressure line, said closure having relatively small fluid inlet and outlet openings leading to and from said holder, said openings being disposed substantially in line with the fluid passageway formed above said closure, whereby a fluid flow will be induced through the chemical holder to impregnate the fluid passing through the fluid pressure line.

In testimony whereof I affix my signature.

WILLIAM R. PULKINGHORN.
